UNITED STATES PATENT OFFICE.

ELMER G. GIBSON, OF HERINGTON, KANSAS.

OIL BURNER.

Application filed April 20, 1923. Serial No. 633,440.

To all whom it may concern:

Be it known that I, ELMER G. GIBSON, a citizen of the United States, residing at Herington, Kansas, have invented certain new and useful Improvements in Oil Burners; and I do hereby declare the following to be a full, clear, and exact description of the invention, such as will enable others skilled in the art to which it appertains to make and use the same.

This invention relates to oil burners, and more particularly to burners of that class adapted for utilization in heating stoves, furnaces, boilers and similar heating structures.

Specifically, the invention relates to a relatively small unit adapted for installation in position to efficiently heat the fire box in such structures as heretofore referred to, as will be more particularly pointed out later.

The object of the invention is the provision of a burner which, while economical from a standpoint of production, is adapted to quickly attain maximum efficiency, and which may be easily installed in operative position.

Other objects will be made apparent in the following specification, taken in connection with the drawings which form a part thereof.

In said drawings,

Fig. 1 is a longitudinal section taken through the fire box of a boiler, equipped with the burner,

Fig. 2 is a vertical section taken on line 2—2 of Fig. 1,

Fig. 3 is an enlarged fragmentary detail of the inner end portion of the burner as shown in Fig. 1,

Fig. 4 is a perspective view of the cover for the oil spreader plate,

Fig. 5 is a top plan view of the spreader plate,

Fig. 6 is a perspective view of the air damper, and

Fig. 7 is a perspective view of the damper support, and flame spreader.

Now referring to the specific embodiment of the invention, here illustrated, the invention is shown as applied to the firebox A of a steam boiler furnace, provided with the usual floors, flash walls, water tubes, and flues, as indicated in Fig. 1. The doors of the fire box have been removed, and the

burner is applied to fill the opening leading to the firebox, as will be understood.

As shown in Fig. 1, the burner comprises a closure 1, adapted to be fitted in position to fill said opening. Rigidly secured to said closure 1, is a downwardly inclined spreader plate 2, and an oil pipe or conduit 3 leads, by means of a proper connection, through said plate 2 from the lower side, said conduit being supplied by oil under pressure, controlled by a valve 3'. The pipe 3 opens at 4 upon the top of said plate 2, and a plurality of oil grooves 5 radiate from said opening 4, to the outer edge of the plate 2, as shown clearly in Fig. 5. The lower front edge of the plate 3 is provided with an oil trough 6, to catch the oil delivered by the grooves 5, the front closure 7 of said trough being serrated, for a purpose to be presently described. A cover plate 8 is fitted to the spreader plate 2, and serves to confine to the grooves 5, the oil delivered by the pipe 3.

Located beneath the spreader plate 2, and spaced therefrom, is an air intake member 9, shown in Fig. 7, and open to the atmosphere, as shown in Fig. 2. The member 9 is equipped with transversely-extending, inwardly-converging walls 10, adapted to form a conduit for the induction of outside air. The inwardly-converging walls 10 serve to trap the air as it is drawn in by the draft in the fire box A, and to increase its velocity at the inner ends of said walls.

A damper 11 is pivotally mounted on trunnions 12, seated in apertures 13 formed in the walls 10 of the intake 9, and an operating rod 14 extends to a point convenient to the operator, whereby the damper 11 may be shifted as desired. The lower edge of the rod 14 may be notched for engagement with the closure 1, whereby to retain the damper 11 in any set position, as will be understood.

The upper portion of the damper 11 is provided with an apron 15, adapted, when the damper is closed, to lie in a plane parallel to the plane of the bottom rear edge 6' of the trough 6, as indicated by dotted lines in Fig. 2, whereby to effectually prevent the passage of air, during the closed position of the damper. As indicated in Figs. 1 and 3, the inner face of the damper 11 is provided with steps or serrations 16, for a purpose to be hereinafter explained.

Below the damper 11, and carried by the front edge of the intake member 9, is a scoop-like flame deflector 17. It is to be noted that the deflector 17 is positioned below the serrations in the front closure 7 of the trough 6, and below the damper 11, and is adapted to catch any unvaporized oil which may drip off the serrations of the trough, or off the serrations of the damper. 10 An overflow pipe 18 leads to the deep portion of the deflector 17, and leads off any excess oil.

In the practical operation of the device as above described, the valve 3' is turned to 15 admit oil to the spreader plate 2. The oil trickles down the grooves 5 until it fills the trough 6, and then passes through the serrations in the upper edge of the wall 7, and falls on to the face of the damper 11, at 20 that time in open position, as shown in full lines, Fig. 1. The oil drops from the damper to the deflector 17, it being understood that the globules of oil are shattered and partially atomized by striking the 25 damper 11 and the deflector 17. The oil may be ignited in any manner, such as by a torch.

As soon as combustion is started the damper is almost closed, and the heat within 30 in the fire box draws air between the walls 10, which air passes above the damper and through the sheet of globules of oil dropping from the trough 6 to the damper, and also below the damper through the sheet of 35 globules falling from the latter to the deflector 17. The passage of air through and transversely of the sheets of globules tends to further atomize the latter, and to form a highly combustible mixture therewith, 40 which tendency is greatly accentuated in proportion to the increase of heat in the fire box, as will be readily understood. As maximum high temperature is approached in the fire box, the spreader plate 2, and the 45 cover plate 8 are so highly heated as to quickly vaporize the oil as it enters and runs down the grooves 5, which vaporization is almost certainly completed as the oil falls from the serrations in the wall 7 and upon the very hot damper 11. Under 50 these circumstances the incoming air, already highly heated between the walls 10, 10, immediately upon passing the damper, contacts oil which is practically vaporized 55 and forms a highly combustible mixture resulting in instant combustion as soon as it reaches the flash zone. At this time the damper 11 may be opened wide and the burner run at maximum efficiency and with 60 a minimum consumption of fuel oil, the deflector 17 directing the flame upwardly and inwardly towards the center of the firebox.

The fuel oil may be any hydro-carbon distillate, such as gasoline, kerosene, or even 65 crude oil.

From the foregoing, it will be obvious that I have produced a unit which may be installed in stoves or furnace structures without the necessity of removing any grates or other original equipment of the fire box, and provided with a draft control which may be adjusted against any wind currents which might otherwise interfere with the efficient operation. 70

While I have here shown a battery of 75 three identical units, it is to be understood that I may just as easily install one unit alone, instead of a battery composed of a plurality of units. The number of units in the installation is dependent upon the conditions which it is desired to meet. 80

Various modifications of the structure herein depicted will be suggested to those skilled in the art, but the invention comprehends all embodiments fairly falling within 85 the scope of the appended claims.

I claim:

1. An oil burner comprising, in combination with an oil conduit, an inclined spreader plate, adapted to receive oil from said conduit, and having a trough at its lower end, a plurality of grooves on said plate adapted to conduct the oil to said trough, a cover plate mounted upon said spreader plate, and a plurality of apertures in the lower wall of said trough, permitting passage of said oil, substantially as described. 90

2. An oil burner comprising, in combination with an oil conduit, an inclined spreader plate adapted to receive oil from the conduit, a trough at the lower end of said plate, an air supply conduit positioned below said plate, a damper pivotally mounted in said air supply conduit below said trough, and apertures in said trough permitting gravitation of said oil to said damper, substantially as described. 100

3. An oil burner comprising, in combination with an oil conduit, an inclined spreader plate adapted to receive oil from the conduit, a trough at the lower end of said plate, an air supply conduit positioned below said plate, a damper pivotally mounted in said air supply conduit below said trough, a deflector mounted below said damper, and adapted to direct flame towards the center of the fire box, and apertures in said trough permitting gravitation of said oil to said damper, substantially as described. 110

4. An oil burner comprising, in combination with an oil conduit, an inclined spreader plate adapted to receive oil from the conduit, a trough at the lower end of said plate, an air supply conduit positioned below said plate, a damper pivotally mounted in said air supply conduit below said trough, a deflector mounted below said damper, and adapted to direct flame towards the center of the fire box, apertures in said trough permitting gravitation of said oil to said 120

125

130

135

damper, and means for taking off any un-vaporized oil accumulated in said deflector, substantially as described.

5. An oil burner comprising, in combination with an oil conduit, an inclined spreader plate adapted to receive upon its upper surface, oil from said conduit, a trough at the lower edge of said plate, a plurality of grooves on said plate adapted to conduct said oil to said trough, apertures in the front edge of said trough permitting the exit of oil when the trough is filled, an air conduit below said trough, a damper pivotally mounted in said air conduit below said apertures, and serrations on the inner face of said damper adapted to receive and temporarily hold oil which gravitates thereon from said apertures, substantially as described.
10. An oil burner comprising, in combination with an oil conduit, an inclined spreader plate adapted to receive, upon its upper surface, oil from said conduit, a trough at the lower edge of said plate, a plurality of grooves on said plate adapted to conduct said oil to said trough, apertures in the front edge of said trough permitting the exit of oil when the trough is filled, an air conduit below said trough, a damper pivotally mounted in said air conduit below said apertures, serrations on the inner face of said damper adapted to receive and temporarily hold oil which gravitates thereon

from said apertures, and a flame deflector located below said damper, substantially as described.

7. An oil burner comprising an inclined spreader plate and means for delivering oil to the top thereof, a trough at the lower edge of said plate adapted to receive oil from the latter, apertures in said trough adapted to permit the escape of oil when the trough is filled, an air conduit below said plate, a damper controlling the passage of air through said conduit and positioned below said trough, and a flame deflector located below said damper, substantially as described.

8. An oil burner adapted for installation into a fire box, comprising, in combination with an oil supply conduit, a spreader plate adapted to confine the oil to a certain area, a trough at the inner edge of said plate, serrations at the upper edge of said trough, a cover plate for said spreader plate adapted to co-operate with the latter in confining the oil, an air intake member mounted below said spreader plate, a damper pivotally mounted on said member, means carried by said member for receiving outside air and directing it past and adjacent said damper, a deflector located below said damper, and means for leading off excess oil received by said deflector plate.

In testimony whereof I affix my signature. 65
ELMER G. GIBSON.
